CLAIM

The ornamental design for an egg/fowl retriever, as shown and described.

DESCRIPTION

FIG. 1 is a perspective view of an egg/fowl retriever showing my new design in open position;

FIG. 2 is a perspective view showing the side opposite that shown in FIG. 1 in a closed position; and

FIG. 3 is a perspective view showing the side opposite FIG. 1 in open position.

FIG. 1

FIG. 2

FIG. 3
